UNITED STATES PATENT OFFICE

149,563

DESIGN FOR A SNOW SLED

John R. Kovar, Anoka, Minn.

Application December 20, 1946, Serial No. 135,640

Term of patent 3½ years

(Cl. D34—15)

To all whom it may concern:

Be it known that I, John R. Kovar, a citizen of the United States and a resident of Anoka, in the county of Anoka and State of Minnesota, have invented a new, original, and ornamental Design for a Snow Sled, of which the following is a specification, reference being had to the accompanying drawing, forming part thereof.

Referring to the drawing:

The single figure shown is a perspective view of a snow sled, showing my novel design.

I claim:

The ornamental design for a snow sled, substantially as shown.

JOHN R. KOVAR.
